DISPLAY CASE AND DISPENSER OF CANNED
AND PACKAGED SUPPLIES

Waldo Edwin Taylor, Randolph Field, Tex.

Application March 23, 1936, Serial No. 70,500

1 Claim. (Cl. 312—48)

This invention relates to dispensers for packaged or canned supplies and has for the primary object the provision of a device of this character which will provide maximum storage for such articles requiring minimum space for its accommodation and is easy to operate under coin control for dispensing articles singularly and to simultaneously feed articles to dispensing position and also having means for recording the number of articles dispensed, besides it will clearly display the kind of articles offered for sale by the device.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a dispensing device constructed in accordance with my invention.

Figure 2 is a sectional view taken on the line 2—2 of Figure 1.

Figure 3 is a sectional view taken on the line 3—3 of Figure 1.

Figure 4 is a fragmentary vertical sectional view illustrating the means for dispensing articles from the device, also showing the coin control mechanism therefor and the means of displaying one of the articles so that the purchaser may easily determine the kind of article the device contains for sale.

Figure 5 is a detail sectional view taken on the line 5—5 of Figure 2.

Figure 6 is a fragmentary vertical sectional view illustrating the gate for the control of the articles from the dispensing device.

Referring in detail to the drawings, the numeral 1 indicates a suitable housing, the front wall 2 thereof being arranged for displaying the kind of article that this device has stored therein for sale, also a coin control mechanism 3 and a window 4 to permit viewing of the face of a conventional type of counter 5. The front wall further is provided with a discharge opening 6 controlled by a dispensing means or gate 7.

The means for displaying the character of article in the device is in the form of a compartment 8 opening outwardly through the front wall and supports upper and lower article engaging elements 9 and 10. The article engaging elements 9 and 10 are similarly constructed to receive therein the ends of either packaged or

canned goods. The article engaging elements 9 and 10 are rotatably supported so that the package or can may be rotated by a purchaser to permit reading of the entire label on the can or package. The article engaging element 9 may be adjusted towards and from the article engaging element 10 so that packages or cans of different lengths may be accommodated therein.

Vertically arranged walls 11 are adjustably mounted on supporting rods 12 secured to opposite sides of the housing. The walls 11 may be adjusted towards and from each other and form sides for superimposed chutes 13. To complete the chutes 13 by cooperating with the side walls are inclined bottom walls 14 suitably secured to the housing 1. The bottom walls 14 incline in the direction of the front wall of the housing and the lowermost chute aligns with the discharge opening 6. The bottom walls of the chutes above the lowermost chute each include pivotally mounted sections 15, the purpose of which is to permit articles in the chutes arranged above the lowermost chute to feed into the latter on the exhausting of articles in the lower chute. The sections 15 are capable of swinging downwardly when unsupported by the articles in the chute therebelow. The chutes may be readily filled through a doorway in the rear wall of the housing and which is normally closed by a hinged door 16. The walls 11 being adjustably mounted permits the widths of the chutes to be varied so as to accommodate packaged or canned articles of varying lengths. The rear wall of the compartment 8 forms an abutment for the lower ends of the chutes arranged above the lowermost chute which will prevent articles in the chutes above the lowermost chute from gravitating therefrom.

The gate 7 is of cylindrical formation and is journaled to the front wall at the discharge opening 6 so as to protrude partly into the housing. The gate has an opening 17 formed in a side thereof and is of a size to permit a package or canned article in the lowermost chute to pass freely therein. A spring 18 acts on the gate to position the latter so that the opening 17 thereof will be in communication with the lowermost chute and secured to the gate is a handle 19 whereby a person may readily obtain a grip thereon for revolving the gate to position the opening 17 outwardly of the housing whereby the article therein may be easily removed. The gate is provided with a notch 20 to be engaged by a holding lever 21 when the gate is in article receiving position, as shown in Figure 4. The 55

holding lever is pivotally mounted to the housing as shown at 22, and is acted upon by a spring 23 for forcing one end in a position to engage with the notch. The holding lever when in engagement with said notch will prevent manual movement of the gate into dispensing position. The other end of the holding lever is associated with a coin chute 24, the entrance of which is indicated at 25, and is located in the front wall 10 of the housing. The movement of a coin through the chute is interrupted by a manually actuated slide 26, one end of which projects beyond the front wall of the housing so as to be grasped for the purpose of permitting the coin to pass fully 15 through the chute and at the same time to rock the holding lever to disengage the latter from the notch of the gate whereby said gate will be free for manual manipulation into dispensing position. A projection 27 is formed on the gate 7 20 and contacts an actuating member 28 of the counter 5 each time the gate is moved into dispensing position. As soon as the gate is manually released from dispensing position, the spring 18 returns the same to article receiving position 25 and the holding lever then immediately engages the notch locking the holding gate against movement into dispensing position until the depositing of a coin in the chute and the actuation of the slide 26. The slide 26 forms no part of this 30 present invention nor the coin chute and is merely indicated generally in the drawings and re-

ferred to briefly herein for the purpose of showing an operative arrangement for the releasing of the holding lever from the notch of the gate.

A device of the character described is simple in construction and operation and will provide maximum storage for either canned or packaged articles and will effectively display the kind of articles and will occupy a minimum space within a store or like place and its use will materially reduce operating costs of the store in that purchasers may easily obtain articles simply by the payment of a proper coin into the device which reduces the number of salesmen or clerks required for the conducting of the store and renders maximum convenience to the purchasers as they do not have to wait for the service of a clerk or salesman in order to purchase their wants. 10 15

Having described the invention, I claim:

A dispensing device comprising a housing having a discharge opening, means for controlling 20 said opening, a plurality of superposed parallel chutes, including a pair of vertically disposed parallel side walls, a plurality of superposed bottom walls disposed between the side walls, a plurality of screw threaded rods passing through 25 said side walls and secured to opposite sides of the housing, for moving the side walls towards and from the bottom walls, and a plurality of nuts threaded on said rods and attached to said 30 side walls.

WALDO EDWIN TAYLOR.
